AUTOMATIC AIR VALVE WITH SWING
CHECK AND BACK PRESSURE CONTROLWilliam C. Groeniger, Columbus, Ohio, assignor
to John B. Pierce Foundation, New York, N. Y.,
a corporation of New York

Application January 29, 1937, Serial No. 122,927

2 Claims. (Cl. 137—69)

My present invention relates to automatic air valves or vacuum breakers, and more particularly to an automatic air valve of the G-fitting type equipped with swing check and back pressure control devices.

My invention is adapted for use in connection with plumbing and water supply systems, and wherein it is essential to prevent water which has once passed out from a source of supply from ever returning to said source of supply under any circumstances. Unless the receptacle for receiving water from a source of supply, as a supply main, is physically and completely separated from the supply main there is always grave danger that under exceptional conditions, such as may arise in the water supply system, some water which has once passed out from the supply system will be siphoned back into the supply system. From the standpoint of public health it is necessary therefore that no siphoning construction in plumbing systems shall ever be capable of acting as a means for redrawing into a water supply system water which has once passed out from such system.

My present invention is adapted to carry out the prime object set out above in that when a device constructed according to my present invention is incorporated in a plumbing system it will prevent the formation of a siphoning condition in the system.

In carrying out my present invention I associate with an air valve of the G-fitting type, a swing back and back pressure control means comprising generally a flap valve, which may be normally open or normally closed as occasion requires, and which G-fitting type valve has associated therewith an air valve which likewise may be normally open or normally closed so as to permit air to be drawn into the plumbing system under normal conditions at all times, and to allow air to be drawn into the plumbing system so as to break up and thus prevent any vacuum condition from being established in the plumbing system.

A feature of my invention is an automatic air valve of the G-fitting type having a swing back and back pressure control device associated therewith.

A feature of my invention is an automatic air valve provided with means for admitting air to the water intake end of the valve upon the establishment of abnormal conditions therein.

Other features of the invention will appear as the description of the invention progresses.

In the accompanying drawings:

Fig. 1 is a view, in sectional elevation, of a valve of the "G" type in which my present invention has been embodied;

Fig. 2 is a sectional plan view taken on line 2—2 of Fig. 1;

Fig. 3 is a bottom plan view of the flap valve arrangement shown in Fig. 1;

Fig. 4 is a view, in sectional elevation, of a modified form of my invention, and

Fig. 5 is a view, in sectional elevation, of a still further modified form of my invention.

Referring to the drawings, and more particularly to Figs. 1, 2 and 3, 10 designates generally an air valve of the G-fitting type constructed of a bottom body member 11, and a top body member 12. Such body members 11 and 12 are hollow and are provided at their cooperating ends with threaded means 13 for securing the members together as a unit. The top member 12 is provided with an internally threaded inlet 14, leading to a chamber 15, formed in said unit, and which chamber is connected by means of passage 16 with a chamber 17, formed in the bottom body 11.

The chamber 17, in the bottom body member 11, connects with a discharge pipe 18, and the lower end of the body member 11 is provided with means, such as a packing nut 19 and packing 20, to form a fluid tight connection between the lower body member 11 and the discharge pipe 18.

At one side of the upper body member 12 and communicating with the chamber 17 in the bottom body member 11 is an arcuate passage 21, at the lower end of which is formed a valve seat 22.

The valve seat 22 lies substantially in the same horizontal plane—as shown in the figures—as lies a valve seat 23, at the lower end of the passage 16 connecting the chamber 15 in the upper body member with the chamber 17 in the lower body member 11.

Within the upper body member 12 and located in the material of such body member between the restricted passage 16 and arcuate passage 22, is a chamber 24. Rotatably mounted on pintles 25 in the chamber 24 is a depending member 26. Such depending member 26 extends into the interior of the lower body member 11 and has secured thereto in any suitable manner an angularly formed supporting framework 27. The framework 27 when in the normal position and supported at the lower end of the depending member 26 is in the position shown in Fig. 1 where it will be apparent that the elements of the framework 27 extend outwardly and down-

wardly from the depending member 26 and form an angle with the valve seats 22 and 23.

Secured to one arm of the framework 27 is a cup valve 28 provided with an integrally formed annular flange valve 29. The cup valve 28 is slotted, as indicated by the numeral 30, and both the cup valve 28 and annular flange valve 29 are secured in position on the arm of the supporting framework 27 by the member 31.

Upon rotation of the framework 27 about the pintles 25 as an axis, and in a clockwise direction as viewed in Fig. 1, it will be apparent that the annular valve 29 will move upwardly and seat against the valve seat 23 formed at the lower end 10 of the restricted passageway 16 of the upper body member 12, and therefore the restricted passageway 16 will be closed. Under such circumstances, however, if the rotative movement above described has been occasioned by the building up of a 15 vacuum condition in the piping system to which the air valve 18 has been attached, air can still flow upwardly through the restricted passage 16 through the slotted opening 30 in the cup valve 28, and the possibility of a siphon condition being built up in the piping system is prevented.

Secured to the other arm of the framework 27 by means 32 is a flap valve 33 which may be of any suitable material such for example as fiber, or rubber, or any other suitable flexible or inflexible material. The normal position of such flap valve 33 is shown in Fig. 1.

Under the normal conditions as existing in Fig. 1, it will be apparent that air from the outer atmosphere may flow freely through the arcuate passage 21, and into the lower body member 11 around the flap valve 33, and that such condition is accentuated under the abnormal conditions which will exist when the annular flange valve 29 engages with the valve seat 23. Under abnormal conditions therefore, air is freely supplied to the arcuate passage 21 and such air will flow upwardly through the cup valve 28 to break down any vacuum condition tending to arise in the piping system.

Under the normal conditions of operation, that is, when water is being drawn from the plumbing system, to which the valve 18 is assumed to be attached, through the upper body 12, the restricted passage 16, through the lower body 11 and into the pipe 18 to a receptacle, the flow of water as above pointed out will rotate the framework 27 in a counterclockwise direction about the pintles 25 as an axis, forcing the valve 33 into association with the valve seat 22 and preventing escape of water through the arcuate passage 21.

This condition will be maintained as long as water is flowing as just described.

With this form of my invention therefore no restriction is offered to the flow of water from the main pipe system to the outlet pipe 18 and under such conditions, because of the operation of the valve 33, no water will leak out of the system through the arcuate passage 21. Also upon the establishment of abnormal conditions in the water supply system the valve 28 will close in the attempt to prevent redrawing of water to the water supply system and the cup valve 28 will open to break up the vacuum condition which will be created in the water supply system. The 60 passage of air through the cup valve 28 will be accelerated by the further opening of the valve 33 which permits air to flow freely through the arcuate passage 21.

Referring now to Fig. 4 there is shown an air valve 18 of the G-fitting type in which the depend-

ing member 26 extends downwardly into the chamber 17 of the bottom body member 11. Such depending member 26 has secured thereto at its lower end a framework 34 to which is attached by means 35 a flap valve 36 which cooperates with the valve seat 23 at the lower end of the restricted passage 16 in the upper body member 12. The framework 34 has attached thereto, and on one side thereof, an arm 37 provided with a weight 38 on its free end which acts as a counterweight and always tends to rotate the framework 34 in a clockwise direction, as viewed in Fig. 4. Such action forces the valve 36 into association with the valve seat 23.

Communication from the passage 16 to the 15 chamber 17 of the lower body 11 therefore is always closed under normal conditions, and will only be opened when water flows from the water supply system through the threaded end 14 and downwardly past the flap valve 36 into the outlet 20 pipe 18.

In this form of my invention the arcuate passage 21 in the portion thereof adjacent the outside of the upper body member 12 is threaded at 39 to receive a clamping member 40 which acts to 25 clamp a resilient breather valve 41 in position in the outer open end of such arcuate passage 21. In this form of the invention as an abnormal condition arises in the water supply system and creates a tendency to build up a siphon condition 30 in the piping, the valve 36 will close, seating on the valve seat 23 and water will be prevented from passing upwardly from the lower body member 11 through the upper body member 12. If the abnormal condition persists or increases, the valve 35 36 leaks, and air will be drawn through the breather valve 41 and such air will pass through the valve 36 thereby breaking up the siphon condition being created.

Referring now to Fig. 5 there is shown therein 40 a construction similar to Fig. 1 but wherein the upper body member 12 has formed integral therewith a chamber 42 opening into the chamber 15 of the upper body member 12 through a passage 43. Such chamber 42 has secured thereto by member 44 a breather valve 45. In this modification also the depending member 26 carries a framework 46 provided with the flap valve 47 associated with the valve seat 23 and the flap valve 48 associated with the valve seat 22. 45

In this modification also the flap valve 47 is normally closed on its seat 23 and therefore and of necessity the flap valve 48 is normally opened so that air is permitted to flow freely through the arcuate passage 21 into the chamber 17 of the 55 lower body member 11. Also the breather valve 45 is normally closed. Under normal conditions therefore only air can flow through the arcuate passage 21 into the chamber 17 of the lower body member 11.

When water is flowing from the water supply system through the upper body member 12 the flap valve 48 will be forced onto its seat 22, thereby preventing access of air to the chamber 17 of the lower body member 11 through the arcuate passage 21, and no water will flow out through the arcuate passage 21.

Upon the building up of an abnormal condition in the water supply system a vacuum will tend to be produced, thereby closing the valve 47 onto its seat 23, and as no air can pass through such valve 47 the building up of the vacuum condition will open the breather valve 45, thus permitting air to flow through such valve and the passage 70

43 into the water supply system, breaking up the vacuum condition being built up.

Whereas I have described my invention by reference to specific forms thereof, it will be understood that many changes and modifications may be made without departing from the spirit of the invention.

I claim:

1. In a back pressure control device the combination of, a body comprised of an upper and a lower member, a chamber formed in the lower member, a passage extending longitudinally through the upper body member, an arcuate passage in said top member, both said passages communicating with the chamber in the lower body member, valve seats formed at the inner ends of the passages in the upper body member, a frame pivotally mounted in the upper body member, valves mounted thereon and associated respectively with the valve seats formed at the exit end of the longitudinal passage and at the inner end of the arcuate passage, and whereby upon back pressure in the valve body the valve associated with the valve seat in the longitudinal passage will engage with said valve seat to prevent egress of water therethrough and whereby the valve associated with the valve seat at the inner end of the arcuate passage will be removed therefrom to permit air to flow into the chamber in the lower body member, and a valve independent of the valve associated with the inner end of the longitudinal passage permitting flow of air

directly into the longitudinal passage while the last said valve is in engagement with the said valve seat.

2. In a back pressure control device the combination of, a body comprised of an upper and a lower member, a chamber formed in the lower member, a passage extending longitudinally through the upper body member, an inlet extending laterally into the longitudinal passage, a breather valve located in said lateral passage, an arcuate passage in the upper body member, both the arcuate passage and the longitudinal passage communicating with the chamber in the lower body member, valve seats formed at the inner ends of the longitudinal and arcuate passages in the upper body member, a frame pivotally mounted in the upper body member, valves mounted thereon and associated respectively with the valve seats formed at the exit end of the longitudinal passage and at the inner end of the arcuate passage, and whereby upon back pressure in the valve body the valve associated with the valve seat in the longitudinal passage will engage with said valve seat to prevent egress of water therethrough and whereby the valve associated with the valve and at the inner end of the arcuate passage will be removed therefrom to permit air to flow into the chamber in the lower body member, and whereby the breather valve in the lateral passage will be opened to permit flow of air into the longitudinal passage.

WILLIAM C. GROENIGER.
